VALVE FOR HEATING APPARATUS

Lewis W. Eggleston, Detroit, Mich., assignor to
 Detroit Lubricator Company, Detroit, Mich., a
 corporation of Michigan

Application April 27, 1933, Serial No. 668,177

5 Claims. (Cl. 137—139)

My invention relates to new and useful improvements in heating apparatus, and more particularly to an apparatus or system for controlling flow of fluid fuel to a heating burner.

5 An object of my invention is to provide a system in which the heating burner is controlled through the medium of a controlling pilot burner.

Another object is to provide in such a system or apparatus means for igniting the controlling pilot 10 burner.

Another object is to provide a novel valve for controlling flow of fuel to the heating burner.

The invention consists in the improved construction and combination of parts, to be more 15 fully described hereinafter and the novelty of which will be particularly pointed out and distinctly claimed.

In the accompanying drawings, to be taken as a part of this specification, I have fully and clearly illustrated a preferred embodiment of my invention, in which drawings—

Figure 1 is a view in front elevation of a burner controlling apparatus embodying my invention;

Fig. 2 is a view of the apparatus in side elevation, having certain parts broken away;

Fig. 3 is an enlarged detail view in section on the line 3—3 of Figure 1;

Fig. 4 is a view in section on the line 4—4 of Fig. 3, and

Fig. 5 is a detail view in section on the line 5—5 of Fig. 4.

Referring to the drawings by characters of reference, I designate generally a supporting framework having a vertical frame member or upright 2 to which is adjustably secured a forwardly extending bracket member 3. A main fuel supply conduit or pipe 4 is supported by the member 3 and preferably seats in a recess 5 formed in the top face thereof. The main pipe 4 has a branch pipe or riser 6 communicating therewith and supported thereby. The branch pipe 6 supports a valve 7 which controls flow of fuel from the pipes 4 and 6 to a main heating burner 8. A pilot burner 9 is positioned adjacent the main burner 8 and serves to ignite the same. This pilot burner 9 is supplied with fuel by means of a pipe line or conduit 10 which is supported, as at 10a, by a horizontal laterally extending frame member 11 having a flange 11a secured to the upper end of the upright 2. The conduit 10 terminates at the pipe 6 and has its end secured and sealed in an outlet port 12 in the pipe 6. The conduit 10 is preferably provided with a control valve 13 for regulating the size of the pilot flame at the burner 9. The frame member 2 has a laterally extending supporting arm 14 which lies beneath the frame member 11 and to which a supply pipe 15 is rigidly secured, preferably by lugs or ears 16 rigid with the pipe 15 and fas-

tened to the arm 14 by screws 17, or the like. The pipe 15 is supplied with fuel from a conduit 15a and is branched at its upper end to provide substantially parallel terminal end portions 18, 19, with the portion 18 overlying the portion 19. The portion 18 supports a controlling pilot burner 20 which is supplied with fuel therefrom by the pipe 15. Extending from the portion 19 and supported thereby, there is an upwardly inclined igniter tube 21 which lies beneath the pilot burner 20 and which terminates at its upper end closely adjacent to the pilot burner 9. The upper end of the tube 21 is closed and sealed by a plug 22, and in the top face of the tube 21 there is a longitudinally extending series of burner ports 23. 15 These ports are closely adjacent to one another and extend from the burner 9 to the burner 20. Flow of fuel through the pipe 15 to the pilot burner 20 and the igniter tube 21 is controlled by a valve 24 in the conduit 15a. The valve 24 is 20 preferably electrically operated and of the solenoid type having its coil supplied with current by the lead wires 25, 26. Operation of the valve 24 is preferably controlled by a thermostatic switch 27 which may be of any desired construction inserted in the lead wire 25 in series circuit with the solenoid coil.

The valve 7 comprises a casing 28 having chambers 29 and 30 therein which are separated by an internal wall or partition 31 through which there is an aperture 32. The chamber 29 has an open side which is closed and sealed by a plate member 33 secured to the casing by screws 34. A gasket, or the like, 35 may be provided to seal the joint between the plate member 33 and the casing 28. Projecting from the outside face of the plate member 33 there is an elongated tubular outlet member 36 having a longitudinal open-ended bore 37 therethrough which opens at its inner end through an outlet port or aperture 38 in the plate member 33 into the chamber 29. The outlet member 36 extends into the bore of a sleeve member 38 carried by the inlet end of the mixing tube 39 of the main burner 8. The mixing tube 39 is provided with air inlet ports 40 which are controlled by a valve plate 41 adjustably screw-threaded upon the sleeve member 38. The free end of the outlet member 36 is provided with a ported plug 42 having a nozzle aperture 43 therethrough for discharging the gas or other fluid fuel into the mixing tube 39. At its inner end the bore 37 is of enlarged internal diameter, as at 44, to provide an annular recess having an inward facing shoulder 45. Positioned in the recess 44 and seating against the shoulder 45 there is an annular valve seat member 46 having a port 47 therethrough. The member 46 extends into the chamber 29 and has its inner end portion beveled, as at 48, to provide a valve seat. Within the chamber 29 there is a valve member 49

49 which cooperates with the seat 48 and which is supported for universal movement by one end of an operating member or lever 50. The valve member preferably comprises a valve disc 51 tightly clamped between opposed peripheral flanges on hollow nut and screw members 52, 53. Within these hollow members there is a supporting pin 54 having a conical head or end portion which seats against the member 53 and which is normally held thereagainst by a coil spring 55 surrounding the pin 54 and held under compression between the nut member 52 and the head of the pin 54. The pin 54 projects through an aperture in the nut member 52 and is rigidly fixed, as at 56, to the lever 50. Adjacent its other end the lever 50 has substantially parallel opposed flanges 57 projecting from the side edges of the lever and toward the plate member 33. The flanges 57 are provided with aligned apertures to receive the end portions of a supporting shaft 58 which is mounted in substantially parallel spaced lugs or ears 59 projecting from the inside face of the plate member 33 and positioned between the flanges 57. The shaft 58 serves as a fulcrum for the lever 50 so that the valve member 49 is pivotally supported for movement toward and from its seat. The valve member 49 is normally urged toward closed position by a spring 60 which is coiled about the shaft 58 between the lugs 59 and which has its end portions engaging the inside face of the plate member 33 and the underside of the lever 50 on the opposite side of the lever fulcrum from the valve member 49.

35 Through the wall of the casing 28 there is an internally threaded bore 61 positioned above the chamber 30 and opening into the chamber 29, being preferably aligned with the bore of the outlet member 36. Adjustably screw-threaded in the bore 61 there is a stem 62 having its ends projecting from the bore. On the end of the stem within the chamber 29 there is a head portion 63 cooperable with the lever 50 and serving as a stop or abutment member to limit opening movement of the valve member 49. The bore 61 is sealed around the stem 62 by packing material 64 held under compression by a packing nut or sleeve 65 screw-threaded in the outer end of the bore 61. It may be noted that the stem 62 may be screwed inwardly so that the head portion 63 will engage the lever 50 and hold the valve member to its seat to prevent flow through the casing.

55 The chamber 30 has an open side which is closed and sealed by a plate member 66 which is substantially parallel to the plate member 33 and which is secured to the casing by screws 67. Within the chamber 30 there is an expansible-collapsible pressure responsive chamber 68 preferably formed by a substantially cylindrical metal bellows 69 having one end secured and sealed, as at 70, in an annular groove or recess formed in the inside face of the plate member 66. The other end of the bellows is closed and sealed by a head member or end wall 71 having a reentrant portion 72 which extends into the chamber 68 and cooperates with the plate member 66 to limit collapse of the bellows 69. The head member 71 rigidly supports a plunger or operating member 70 which is preferably screw-threaded or otherwise secured in a substantially cylindrical recess 74 in the member 71 and portion 72. Adjustably screw-threaded on the plunger member 73 there is an abutment member 75 preferably in the form of a sleeve having an annular flange against

which is seated one end of a coil spring 76. The spring 76 surrounds the plunger member 73 and at its other end engages a packing disc or ring 77 seating on the wall 31. In the wall 31 there is an annular packing material recess 78 which opens into the chamber 30 and which surrounds the free end of the plunger member 73. The recess 78 contains suitable packing material which serves to seal the aperture 32 around the plunger 73 and which is held in the recess 10 and under compression by the packing ring 77 and the spring 76. The plunger member 73 has a longitudinal bore 79 in which an operating member 80 is reciprocably mounted. The member 80 projects from the end of the plunger member 73 and is normally held in its outward or extended position by a resilient cushioning spring 81 positioned in the bore 79. Outward movement of the member 80 is limited by a head portion 82 cooperating with an annular shoulder in the 20 bore 79. The member 80 extends into the chamber 29 for cooperation with the lever 50 and is operable upon expansion of the chamber 68 to engage the lever 50 on the opposite side of shaft 58 from the valve member 49. The member 80 is preferably provided with a conical end portion adapted to seat in a conical recess 83 formed in the lever 50. Through the plate member 66 there is a passage 84 which opens at one end into the chamber 68 and which at its other end opens into a passage 85 in a boss 86 projecting from the plate member 66. The passage 85 connects to a tube 87 which extends to the controlling pilot burner 20. The free end portion of the tube 87 serves as a bulb element, preferably being wrapped or coiled, as at 88, around the burner 20 and is secured in position by a clamp 89. The tube 87 and chamber 68 comprise a power means or thermostat and are charged with a suitable volatile liquid which will expand and contract in 40 response to change of temperature. After the tube and chamber have been charged, the end of the tube 87 is closed and sealed, as at 90. The casing 28 has a depending tubular extension 91 which provides an inlet passage to the chamber 45 29. The extension 91 seats on and communicates with the branch pipe 6 to which it is secured by a sleeve nut 92.

The operation of my apparatus is as follows: The pilot burner 9 is ignited and the size of 50 the flame is regulated by the valve 13 so as to provide sufficient flame to ignite the main burner 8 and the gas issuing from the ports 23 in the igniter tube 21. If the thermostat 27 now closes the circuit through the valve 24 to permit flow 55 through the conduit 15* to the pipe 15, the gas will flow through the igniter tube 21 and also be discharged from the pilot burner 20. The gas issuing from the ports 23 in the igniter tube will be ignited adjacent the constantly burning pilot 60 9, and due to the close proximity of the ports 23 the flame will carry down the tube 21 until the gas issuing from the ports 23 adjacent the burner 20 is ignited, when the burner 20 will be 65 ignited thereby. Ignition of the burner 20 will heat the volatile fluid in the coil or bulb 88 and create a pressure transmitted through the tube 87 into the chamber 68. The pressure thus created in the chamber 68 will expand the bellows 69 against the force of spring 76. As the plunger member 73 moves outward and into the chamber 29, the operating member 80 will engage the lever 50. Continued movement of the plunger member 73 as spring 76 collapses will rotate the lever 50 about the shaft 58, overcoming the light 75

spring 60 and moving the valve member 49 toward open position. Opening of the valve member 49 will permit gas to flow through the valve 7 into the mixing tube 39 where the gas will be mixed with the proper proportion of air for burning at the main burner 8. The gas supplied to the main burner 8 will be ignited by the constantly burning pilot burner 9. When the solenoid valve 24 is closed by breaking of the circuit at 10 the thermostat 27, for example, the supply of gas to the controlling pilot burner 20 and the igniter tube 21 will be cut off. Extinguishment of the pilot burner 20 will permit the coil or bulb 88 to cool and thereby relieve the pressure in the 15 chamber 68 so that the spring 76 will retract the plunger member 73 and its operating member 80 from the lever 50 to permit the spring 60 to move the valve member 49 to closed position. The extent to which the valve member 49 can be opened 20 may be regulated by the position of the head portion 63. If the valve member is limited in its opening movement by engagement of the lever 50 with the portion 63 before the chamber 68 has reached its limit of expansion, then the spring 25 81 will permit relative movement between the member 80 and the plunger member 73 so that the plunger member 73 can continue to move without injuring the parts of the valve.

What I claim and desire to secure by Letters 30 Patent of the United States is:

1. In an apparatus of the character described, a hollow casing having a partition dividing said casing internally into a longitudinal chamber having relatively transversely directed inlet and outlet ports and a substantially cylindrical chamber positioned intermediate said inlet and outlet ports and with its longitudinal axis substantially parallel to the axis of said outlet, a valve member in said longitudinal chamber and cooperative with said outlet to control flow through said longitudinal chamber, a lever operatively connected to said valve member and extending longitudinally of said longitudinal chamber and into proximity to said outlet port, said partition having an aperture therethrough coaxial with said outlet and in overlying relation to the end of said lever, a plate member closing and sealing said other chamber and having pressure responsive means sealed thereto, a plunger extending through said aperture and operable to transmit movement from said responsive means to said lever, and a coil spring surrounding said plunger, said spring abutting said partition and resisting movement of said responsive means whereby to regulate the operation of said valve member.

2. In an apparatus of the character described, a hollow casing containing a partition dividing said casing internally into separate chambers having oppositely directed open sides, one of said 60 chambers having an inlet opening through a side wall thereof, a plate member closing and sealing the open side of said one chamber and having an outlet aperture, a valve member in said one chamber controlling flow through said aperture, a lever supported by said plate member and operatively connected to said valve member, said partition having an aperture connecting said chambers, a closure member for the open side of said other chamber, pressure responsive means 65 in the other of said chambers and carried by said closure member, a plunger having a lost-motion means reciprocably supported in and projecting through said aperture and being operable to

transmit movement from said responsive means to said lever, a spring resisting movement of said lever, and a coil spring surrounding said plunger and resisting movement of said responsive means.

3. In an apparatus of the character described, 5 a casing containing a partition dividing said casing into separate chambers, one of said chambers having an inlet, a removable plate member closing a side of said one chamber and having an outlet port, a valve member in said one chamber cooperable with said port and controlling flow therethrough, a lever carried by said plate member and operatively connected to said valve member, said partition having an aperture in registry with one end of said lever, a plunger, an adjustable abutment member in the other of said chambers and longitudinally movable along said plunger, a coil spring in the other of said chambers and held under compression between said partition and said abutment member, said plunger extending through said aperture and being adapted to engage said lever end to move said valve to open position, and a packing medium surrounding said plunger and positioned in said other chamber to seal said aperture whereby to 20 prevent fluid communication between said chambers.

4. A valve of the character described, comprising a hollow casing having an inlet and an outlet and containing a valve port, a lever fulcrum in said casing, a valve member carried by said lever and cooperating with said port to control flow through said casing, a wall of said casing having an aperture therethrough registering with said port, an adjustable stop member 30 screw-threaded into said aperture and projecting at its opposite ends into and from said casing, the inner end of said stop member cooperating with said valve member to limit opening movement thereof and to move said valve member to closed position, thermostatic means 40 co-operable with said lever to actuate said valve member, and a lost-motion connection between said thermostatic means and said valve member whereby said stop member can move said valve 45 member to closed position irrespective of the operation of said thermostatic means.

5. A valve of the character described, comprising a casing having a flat open side, a flat closure plate secured to and closing said open side, 50 an annular valve seat member projecting from said closure plate and defining a valve port, a valve member seating on said seat member to prevent flow through said port, supporting lugs projecting from said closure plate and carrying 55 a bearing member, a lever having side flanges pivotally supported on said bearing member, a spring surrounding said bearing member between said flanges and held under compression between said closure plate and said lever whereby to urge 60 said valve member to closed position, said lever having a recess intermediate said flanges, a plunger projecting into said casing and engageable in said recess to move said lever toward open position, temperature responsive means to move 65 said plunger into engaging relation with said lever, and an adjustable stop member threaded through a wall of said casing and cooperable with the valve carrying end of said lever to overcome said spring and move said valve to closed position. 70

LEWIS W. EGGLESTON.
